UNITED STATES PATENT OFFICE

SAMUEL B. SMITH, OF ROCKY RIVER, OHIO

VARIABLE PITCH PROPELLER

Application filed January 16, 1931. Serial No. 509,148.

The invention relates to variable pitch propellers of the type in which the pitch can be changed during flight.

Considerable difficulty has been experienced in designing and building variable pitch propellers which are practical and stand up when in service. Moreover, heretofore attempted types of variable pitch propellers were adapted with difficulty to standard makes of motors and to standard airplanes and airships, chiefly because the variable pitch propellers and the operating means, therefor, require considerable room and necessitate either a special propeller shaft or crankshaft which is somewhat longer than the one usually employed. Again no means have been provided for positively and adjustably limiting the pitch of the propeller.

The general object of the invention is to overcome the foregoing difficulties and disadvantages of the prior art by providing a variable pitch propeller which is adaptable to standard propeller shafts, and which has improved means controlling the pitch of the blades.

It is also an object of the invention to provide adjustable means for positively limiting the pitch of the propeller blades.

The above and other objects of the invention are achieved by the apparatus illustrated in the accompanying drawings and described below, it being understood that the invention is not limited to the specific details shown and described.

In the drawings:

Figure 1 is a longitudinal sectional view through the hub embodying the invention;

Figure 2 is a sectional view taken on line 2-2 of Figure 1;

Figure 3 is a sectional view taken on line 3-3 of Figure 1;

Figure 4 is a sectional view taken on line 4-4 of Figure 1;

Figure 5 is an enlarged sectional view taken on line 5-5 of Figure 1;

Figure 6 is a fragmentary view taken on line 6-6 of Figure 10;

Figure 7 is a sectional view taken on line 7-7 of Figure 6;

Figure 8 is a sectional view taken on line 8-8 of Figure 6;

Figure 9 is an elevation of the gear carrying member and worm incorporated in the invention; and

Figure 10 is an enlarged sectional view taken on line 10-10 of Figure 5.

The present invention relates to and presents certain improvements over the copending application of Glenn R. Brooks, Serial Number 449,802, filed May 5, 1930.

Referring to the drawings, the numeral 11 indicates a propeller shaft or crankshaft of a motor (not shown) which shaft 11 is journaled in suitable bearings 12 in a motor frame 13.

Keyed to the shaft 11 by a key 16 is hub 14 formed with blade carrying sleeves 15, which may be formed with the hub or which may be secured thereto by welding or brazing. The hub 14 is fixed to the shaft 11 so that it cannot work loose by threading the end of the shaft 11 and providing a cap 17, which is locked in place by a sleeve 18, threaded in opposite hand to the cap 17. The cap 17 and sleeve 18 are locked together by a removable spring 19 fitting in aligned holes therein.

A propeller blade 21 having a cylindrical end 22, threaded at its end with a buttress thread 23 is received in each sleeve 15. A combined nut and worm gear 24 is threaded on the thread 23 and locked in place by screws 25. In order to allow the blades to turn freely in the sleeves even when under great operating stress, a plurality of ball bearings 26 are provided between the ends 22 of the blades and the sleeves 15. In addition the ends 22 of the blades are preferably formed with cylindrical bosses 27, which are jour-

naled by suitable bearings 28 in sockets formed in the hub 14.

Each blade assembly is held in place by means of a ring 31 which is buttress threaded with the sleeve 15. Each assembly is preferably packed with grease which is retained by a gasket 32.

Referring particularly to Figure 5, it will be seen that the hub 14 is formed with four housings 33, 34, 35 and 36, of which 33 and 34, and 35 and 36 respectively are opposite and parallel. Journaled in the housings 33 and 34 are worms 37 and 38 which engage with the worm gears 24 on the inner end of the propeller blades 21. The shafts of the worms 37 and 38 are extended adjacent the housing 36 and are provided with worm gears 39 and 40.

In the housing 36 is (see Figure 10) journaled the means through which the worm gears 39 and 40 are driven, which means also serves to adjustably limit the extent of pitch movement of the blades. These means include a pair of left- and right-threaded worms 42 and 43, which are secured on opposite ends of a tube 44. The worms are threaded unto the tube 44 and the worm 42 is turned on very tightly while the worm 43 is not run down so tight, but is locked by means of a pin 49, which engages in slot 57 of tube 44. The worms 42 and 43 are journaled on a rod 45, which is threaded along its middle and which is supported and positioned by plugs 46 and 47 screwing into the end of the housing 36. The plug 46 and shaft 45 make a sliding but non-rotative fit as at 48, so that the rod cannot turn after the parts are assembled.

Journaled on the tube 44 is a gear 50 having a hub 51 which is positioned midway between the worms 42 and 43 by means of sleeves 52. Slidably mounted on the tube 44 at the ends of the hub 51 of the gear 50 are collars 53 which are urged towards the hub 51 through the agency of curved spring washers 54. The contacting ends of the collars 53 and hub 51 are formed with opposite direction clutches 55 and 56 of the claw type. (See Figures 6 and 8.) The tube 44 is formed with a slot 57 and the collars 53 are splined to the tube by pins 58 which engage in the slot. A pair of round nuts 61 are threaded on the rod 45 and are provided with lugs 62 which slide in the slot 57. The lugs 62 engage with the pins 58 at the end of the travel of the nuts 61 to disengage the clutches as hereafter more fully explained.

The housing 35 is in reality solid and serves merely as a counterbalance for the housing 36 and the means therein. Any amount of metal necessary to correctly counterbalance the unit can be removed from both ends of the housing 35, after which they are closed by suitable caps.

Referring particularly to Figures 1 and 2, means are provided to rotate the gear 50,

which means include a gear carrying member 64 splined to sleeve 65, fixed to a bearing 66, which is in turn secured to the frame 13. The member 64 is formed with right and left threaded worms 67 and 68, either of which are adapted to co-operate with the gear 50 upon movement of the member 64.

In order to control the position of the member 64 the bearing 66 is formed with a peripheral groove, in which is received a ring 71 which can be moved in the groove by a handle 72 through any suitable operating means 73. The ring 71 is provided with a plurality of inwardly extending pins 74 which move in circumferential slots 75 in the bearing 66 and sleeve 65 and slots 76 at an angle to the circumferential in the gear carrying member 64. In this manner when the ring 71 is rotated through an arc the gear carrying member is moved longitudinally or axially.

The shaft 11 is preferably threaded and provided with a nut 77 which secures the bearing 12 in place. Any suitable gasket means may be provided as at 78 and 79 between the stationary and moving portions of the assembly in order to hold the lubricant in the desired places.

The operation is briefly as follows: For the adjustments of the limits with the motor stopped, the worm wheel 40 in the housing 34 is first removed, then the cap 47 in the housing 36 is unscrewed and the whole unit is pulled from the housing 36. The pin 49 is removed and the worm 43 is screwed off the tube 44, allowing the collar 53 and spring washer 54 to be pulled off the tube, which allows the rod 45 with the nuts 61 thereon to be removed. The nuts 61 are now adjusted to any determined position apart and from the ends of the rod. The above operations are reversed and the unit is replaced in the housing 36.

With the motor running, the pitch of the propeller blades can be changed by moving the ring 71 through the agency of the operating means 73. The circumferential movement of the pins 74 secured to the ring 71 is transmitted into axial movement of the member 64 by way of the slots 75 and 76, so that either worm 67 or 68 can be brought into engagement with the gear 50. The worms 67 and 68 do not rotate but the rotation of the propeller hub 14 causes the gear 50 to travel around the worm so that the relative movement between the gear and worm is the same as if the worm were turning.

As the nuts 61 are somewhere intermediate of the pins 58 the turning gear 50 will transmit motion through one or the other of the clutches 55 or 56, dependant on which way the gear is turning, to one of the collars 53, which in turn will rotate tube 44 and the worms 42 and 43 fixed thereto.

The worms 42 and 43 co-operate with the worm gears 39 and 40 to turn the worms 37

and 38 which engage with the gears 24 secured to the inner ends of the propeller blades 21. The gear reduction is very large, so that a large number of revolutions of the propeller hub causes a very small movement 5 of the blades about their longitudinal axes.

The blades can be stopped at any pitch desired by merely returning the worm carrying member 64 to its neutral position. By 10 moving the member 64 in the other direction the pitch is changed in a reverse direction. In this manner the pitch of the propeller blades can be changed and adjusted at will while the propeller is in operation. The 15 plurality of frictionless bearings 26 which journal the blades in the sleeves 15 allow the pitch to be varied even when the blades are under the most severe operating stress.

The mechanism encased in the housing 36 limits the extent to which the pitch of the 20 blades can be changed. For example: With the nuts 61 substantially as shown in the drawings, assume that the member 64 has been moved axially to throw one of the 25 worms 67 or 68 into engagement with the gear 50. The rotating gear 50 will drive either the one or the other of the collars 53 through either clutch 55 or 56, depending on its direction of rotation. The collar 53 will 30 turn tube 44 due to the pin 58 engaging in the slot 57, which tube will in turn rotate the worms 42 and 43, and through the other gearing change the blade pitch. Now the tube 44 when it turns will also turn the nuts 61 as 35 the lugs 62 thereof engage in the slot 57 which causes the nuts to travel along the threaded rod 45 which is held from turning by the square end 48.

The continued rotation of the gear 50 will 40 thus cause the nuts 61 to engage with the one or the other of the pins 58 held by a collar 53 which will cause the collar to be moved outwardly on the tube 44 against the action of the spring 54, which movement will dis- 45 engage the clutch 55 or 56, so that further rotation of the gear 50 will not transmit any motion to the tube 44 or worms 42 and 43.

Rotation of the gear 50 in the opposite 50 direction will cause the nuts 61 to travel in the other direction to disengage the clutch adjacent that end of travel in a like manner. It will be understood that the clutches 55 and 56 are of opposite direction so that when 55 one is disengaged by the nuts 61, the other will slip so that no drive is given the tube 44. By initially adjusting the positions of the nuts 61 on the threaded rod 45, as above de- 60 scribed, it is possible to provide any desired limits beyond which the blade pitch cannot be changed. In this manner the blades can be adjusted exactly and positively to any desired pitch. This construction also eliminates the necessity of pitch angle recording means.

In accordance with the patent statutes

only one specific embodiment of the invention has been described and illustrated. However, it will be understood that the scope of the invention is not limited thereto, but is defined by the appended claims.

70

What is claimed is:

1. In a variable pitch propeller, a hub, a propeller blade mounted in said hub, gear means carried on said hub and connected with said blade, non-rotative gear means 75 mounted adjacent said hub, means for moving said gear means relative to each other to cause them to engage whereby the pitch of the propeller blade can be varied and adjustable means in said first named gear 80 means for positively controlling the limits of the pitch variation.

2. In a variable pitch propeller, a hub, a propeller blade mounted in said hub, gear means carried on said hub and connected 85 with said blade, gear means mounted adjacent said hub, means to engage said last named gear means with said first named gear means, whereby the pitch of the propeller blade can be varied and adjustable means in 90 said first named gear, means for positively controlling the limits of the pitch variation.

3. In a variable pitch propeller, a hub, a propeller blade mounted in said hub, gear means carried on said hub and connected 95 with said blade, gear means mounted adjacent said hub, means to engage said last named gear means with said first named gear means, whereby the pitch of the propeller blade can be varied and adjustable means 100 for positively controlling the limits of the pitch variation.

4. In a variable pitch propeller, a hub, a propeller blade mounted in said hub, gear means carried on said hub and connected 105 with said blade, non-rotative gear means mounted adjacent said hub, means for moving said gear means relative to each other to cause them to engage whereby the pitch of the propeller blade can be varied and means 110 for positively controlling the limits of the pitch variation.

5. In a variable pitch propeller, a hub, a propeller blade mounted in said hub, gear means carried on said hub and connected 115 with said blade, gear means mounted adjacent said hub, means to engage said last named gear means with said first named gear means, whereby the pitch of the propeller blade can be varied and adjustable means in 120 said first named gear, said adjustable means including a clutch connection in said first named gear means and means for disengaging said clutch connection at the desired limit of the pitch variation.

125

6. In a variable pitch propeller, a hub, a propeller blade mounted in said hub, gear means carried on said hub and connected with said blade, gear means mounted adjacent said hub, means to engage said last 130

named gear means with said first named gear means, whereby the pitch of the propeller blade can be varied and adjustable means in said first named gear, said adjustable means including a clutch connection and means for disengaging said clutch connection at the desired limit of the pitch variation.

7. In a variable pitch propeller, a hub, a propeller blade mounted in said hub, gear means carried on said hub and connected with said blade, gear means mounted adjacent said hub, means to engage said last named gear means with said first named gear means, whereby the pitch of the propeller blade can be varied and adjustable means in said first named gear, said adjustable means including a clutch connection in said first named gear means.

8. In a variable pitch propeller, a hub, a propeller blade mounted in said hub, means for changing the pitch of the propeller while in operation and adjustable means for positively controlling the limits of pitch variation.

9. In a variable pitch propeller, a hub, a propeller blade mounted in said hub, means for changing the pitch of the propeller while in operation and adjustable means for positively controlling the limits of pitch variation, said adjustable means including a clutch connection in the first named means and means for disengaging said clutch connection at the desired limit of the pitch variation.

10. In a variable pitch propeller, a hub, a propeller blade mounted in said hub, means for changing the pitch of the propeller while in operation and adjustable means for positively controlling the limits of pitch variation, said adjustable means including a clutch connection in the first named means.

11. In a variable pitch propeller, a hub, a propeller blade mounted in said hub, gear means carried with said hub and connected with said blade, non-rotative gear means mounted adjacent said hub, means rotatable about the hub axis for moving said last named gear means axially of said hub to cause the engagement of the gear means whereby the pitch of the propeller blade can be varied and means for positively controlling the limits of pitch variation.

12. In a variable pitch propeller, a hub, a propeller blade mounted in said hub, gear means carried with said hub and connected with said blade, a sleeve, spaced spiral gears on said sleeve, and a shifting means having a pin and slot connection with the sleeve for shifting said sleeve on the hub to cause the spiral gears to selectively engage with said first named gear means.

13. In a combination in a variable pitch propeller, a hub, a propeller blade mounted in said hub and adapted for movement about a longitudinal blade axis, gear means carried with said hub and connected to said blade,

a gear carrying member mounted adjacent said hub for sliding movement, gears mounted in spaced relation on said gear carrying member, means rotatable about the hub axis for moving said gear carrying member along the hub to engage the one or the other of the gears with said gear means on the hub whereby the blade pitch can be changed, and means for positively controlling the limits of pitch variation.

14. In combination in a variable pitch propeller, a hub, a propeller blade mounted in said hub and adapted for movement about a longitudinal blade axis, gear means carried with said hub and connected to said blade, a gear carrying member mounted adjacent said hub for sliding movement, gears mounted in spaced relation on said gear carrying member and means making a slot and pin connection with said gear carrying member and rotatable about the hub axis for moving said gear carrying member along the hub to engage the one or the other of the gears with said gear means on the hub whereby the blade pitch can be changed.

15. In a variable pitch propeller, a hub, a propeller blade mounted in said hub, gear means carried with said hub and connected with said blade, non-rotative gear means mounted adjacent said hub and means rotatable about the hub axis for shifting said last named gear means along said hub to cause the engagement of the gear means whereby the pitch of the propeller blade can be varied and adjustable means in said first named gear means for positively controlling the limits of the pitch variation.

16. In a variable pitch propeller, a hub, a propeller blade mounted in said hub, gear means carried with said hub and connected with said blade, non-rotative gear means mounted adjacent said hub and means rotatable about the hub axis for moving said last named gear means axially of said hub to cause the engagement of the gear means whereby the pitch of the propeller blade can be varied and adjustable means in said first named gear means for positively controlling the limits of the pitch variation, said adjustable means including a clutch connection in said first named gear means and means for disengaging said clutch connection at the desired limit of the pitch variation.

17. In a variable pitch propeller, a hub, a propeller blade mounted in said hub, gear means carried with said hub and connected with said blade, non-rotative gear means mounted adjacent said hub and means rotatable about the hub axis for moving said last named gear means axially of said hub to cause the engagement of the gear means whereby the pitch of the propeller blade can be varied and adjustable means in said first named gear means for positively controlling the limits of the pitch variation said adjustable means in-

cluding a clutch connection in said first named gear means.

18. In a variable pitch propeller, a hub, propeller blades mounted in said hub, means for changing the pitch of the propeller while in operation, and means located on the propeller and actuated by said pitch changing means for automatically throwing out of operation said pitch changing means at a predetermined point for controlling the limits of pitch variation.
